US0D1076727S

(12) **United States Design Patent** (10) Patent No.: **US D1,076,727 S**
(45) Date of Patent: ** May 27, 2025

(54) **ELECTRIC BICYCLE**

(71) Applicant: **G-Force Inc**

(72) Inventor: **Xin Wang**, Xuzhou (CN)

(73) Assignee: **G-Force Inc**

(**) Term: **15 Years**

(21) Appl. No.: **29/962,843**

(22) Filed: **Sep. 13, 2024**

Related U.S. Application Data

(63) Continuation-in-part of application No. 29/874,481, filed on Apr. 20, 2023, now Pat. No. Des. 1,051,777.
